(57) **CLAIM**

The ornamental design for a food container, as shown and described.

DESCRIPTION

FIG. 1 is a top isometric view of a food container showing our new design.

FIG. 2 is a bottom isometric view thereof.

FIG. 3 is a top plan view thereof.

FIG. 4 is a bottom plan view thereof.

FIG. 5 is a front elevational view thereof.

FIG. 6 is a rear elevational view thereof.

FIG. 7 is a left side elevational view thereof.

FIG. 8 is a right side elevational view thereof.

FIG. 9 is a top isometric view of the cover portion of the food container, separated from the base portion to show aspects of the design that are not visible when combined; FIG. 10 is a top isometric view of the base portion of the food container, separated from the cover portion to show aspects of the design that are not visible when combined; FIG. 11 is a cross sectional view taken from FIG. 3, in the direction of line 11-11;

FIG. 12 is a cross sectional view taken from FIG. 3, in the direction of line 12-12;

FIG. 13 is an exploded view of FIG. 11, showing the cover separated from the base;

FIG. 14 is an exploded view of FIG. 12, showing the cover separated from the base;

FIG. 15 is cross sectional view taken from FIG. 3, in the direction of line 15-15;

FIG. 16 is a cross sectional view taken from FIG. 3, in the direction of line 16-16;

FIG. 17 is an exploded view of FIG. 15, showing the cover separated from the base; and,

FIG. 18 is another exploded view of FIG. 15, showing the cover separated from the base.

The stippling shown in the Figures represents surface shading and not surface ornamentation.

1 Claim, 15 Drawing Sheets
